REGISTRATION CONTROL FOR PIPE
ORGANS

Donald S. Barrows, Rochester, N. Y.

Refiled for abandoned application Serial No.
306,726, September 18, 1928. This application
January 28, 1932, Serial No. 589,519

10 Claims. (Cl. 84—345)

The invention relates to pipe organs and has special reference to the control of registration.

The principal object of the invention, generally stated, is to provide means whereby the player may more conveniently prepare for a change in the registration, while playing, and in advance of the time at which he desires the new registration to become effective.

It is well known that on modern organs having four or more manual key boards and a large number of stop knobs or keys and couplers, the problem of securing a simultaneous change in registration for several divisions of the organ has heretofore usually been solved by one or both of two methods, viz: a large number of visible or absolute combination actions controlled by pistons under the manuals or toe studs over the pedals, or by the combination system known as blind or dual, controlled by similar pistons or toe studs.

With the visible combination system, the knobs, keys or tablets controlling the action of stops or couplers desired for a certain registration are simultaneously moved to the "on" position by the pressure of the player on a piston or toe stud, the combination mechanism having previously been set by the player to move these particular knobs, keys or tablets, on the pressing of a particular piston or stud, and all other stops and couplers in the same organ division are moved to the "off" position by the same piston pressure.

It should be understood that in modern organs having electric or electro-pneumatic actions the knob or other controlling means when in the "on" position simply completes an electrical circuit, thereby energizing a suitable mechanism which admits air to a chest division or to the motor of a coupler switch, or of some similar device. It is, therefore, possible that a stop or coupler may be "on" or "off" without reference to the position of the console controlling means by completing or breaking the proper electrical circuit through other means.

The blind combination system is usually set in the same or equivalent manner as the visible system and is operated by similar pistons or toe studs, but it acts directly on the stop or coupler circuits regardless of the position of and without moving the knobs, keys or tablets. A blind combination may act to retain the active circuits which are visibly "on" or more usually it may break all circuits which it is not set to close. Under the latter arrangement the position of the stop knobs or keys and couplers may be changed by hand or by an auxiliary visible combination system while the organ action is under the control

of a blind combination, without change in the actual registration until the blind combination is released, whereupon the active circuits immediately respond to the position of the knobs, keys or tablets at the time of such release.

With the more usual visible combination system, the large number of combinations necessary for control of all divisions of the organ adds materially to the cost of the organ and one, two or more combination pistons must be pressed simultaneously and at the exact instant a change in registration is desired.

While the blind or dual combination system permits advance registrational preparation through the moving of knobs, keys or tablets by hand or by a separate visible combination system controlled by other pistons, it is not favored by many players because there is usually no visible indication as to which stops or couplers are actually effective, and with a large number of blind combinations this places a heavy burden on the player's memory and seriously handicaps him while playing an organ with which he is not perfectly familiar.

It is with the above various facts in view that I have devised the present invention which has for an important object the provision of a stop action system whereby the player may, at his option, control the registration in the usual manner by hand movement of stop and coupler controls, or by the visible combinations at the moment of desired change; or whereby he may prepare for or set a registration to be played at a later time without disturbing the then present registration, means being provided whereby the advance registration may be made effective when the change is desired, it being a feature that as many corrections or changes in the advance setting as desired may be made during a present registration without having any effect thereupon and without requiring the operation of any special release means.

Another object of the invention is to provide an apparatus of this character which may be operated by a combination of mechanical and electrical means or by the combination of electrical and pneumatic means, depending upon the preference of the manufacturer and other conditions which may exist, such as the type of organ, etc.

Another object of the invention is to provide a control apparatus of this character which will not involve any undue complexity and which may consequently be installed at reasonable cost and

which will, moreover, be highly efficient in action and a general improvement in the art.

To the attainment of the foregoing and other objects and advantages, as will hereinafter appear, the invention preferably consists in the various embodiments to be hereinafter more fully described and claimed, and illustrated in the accompanying drawings in which:—

Figure 1 is a somewhat diagrammatic view of 10 a portion of a pipe organ of the electrically operated type showing a mechanical means for effecting future setting of the registration, parts of the apparatus being shown in elevation and other parts in section.

Figure 2 is a plan view with parts broken away 15 and in section.

Figure 3 is a detail cross section taken on the line 3—3 of Figure 1.

Figures 3a, 3b and 3c are detail sectional views, 20 taken respectively on the lines 2—2, b—b, and c—c of Fig. 1, illustrating a contact arrangement.

Figure 4 is a somewhat diagrammatic view 25 showing a different mechanical means for effecting electrical control of a future registration.

Figure 5 is a view, partly in section and partly 30 in elevation, with diagrammatic features included, illustrating a system of electro-pneumatic control for the registration.

Figure 6 is a sectional view of an air pressure 35 control means used in connection with this modification.

Referring to the drawings in detail, it will be 40 observed that I have made no attempt to illustrate any details of the organ construction itself 45 as the invention relates only to the means for controlling the registration. Insofar as the general organ construction is concerned, it is thought sufficient to show a portion of a pipe chest 1 and a stop action chest 2, each individual stop action being controlled by an electro-magnet 3 50 so arranged and related to a valve mechanism and fluid pressure supply, not shown, that when the magnet is energized all the pipes 4 in that particular rank (stop) are subject to pressure air and will sound when the proper action key (not shown) is pressed.

The stop key, which is essentially of more or 55 less ordinary pattern, is indicated at 5 and is rockably mounted on a fulcrum rod 6 and adapted to be held in the "on" or "off" position by a suitable spring 7 which engages the key and which likewise engages some stationary portion 8 of the organ. This key 5 carries a segment 9 here represented as formed with an arcuate slot 10, each end of which contains a pair of followers 11 between the respective members of each pair of which are springs 12 and 13. Likewise fulcrumed upon the rod 6 is an arm 14 preferably of yoke form and straddling the segment, the yoke having a bight portion 15 carrying a filler 16 and extending through the slot 10 with the ends of the filler engaging between the inner followers 11. Normally, this arm or yoke is held in intermediate position with respect to the segment by the 60 springs 12 and 13. The yoke is independently movable with respect to the key 5 but it is apparent that upon movement of the key the yoke or arm would be correspondingly moved if no means were provided for preventing it. However, I provide a lock bar 17 which is capable of movement 65 towards or away from yoke arm 14 as the result of actuation of some control means, not shown, and this lock bar is adapted to be moved into obstructing relation to the projecting end of the 70 yoke or arm 14, as shown by full lines in Figure 1,

the non-obstructing position being shown by dotted lines in the same figure. It is clear that when the lock bar is in the obstructing position illustrated, downward movement of the key 5 will not cause movement of the yoke or arm 14. The result of movement of the key 5 will be upward movement of the segment 9 and compression of the spring 13 so that upon subsequent movement of the lock bar 17 to non-obstructing position the power stored in the spring 13 will throw the yoke or arm 14 upwardly. The purpose of this and the advantage taken of the action will be explained hereinafter.

Arranged for engagement with yoke or arm 14 are contacts 18, 19 and 24. Contact 18 is in continual engagement with 14 regardless of the position of the latter and is connected by a conductor 20 with one terminal of a generator or other current supply source 21 which has its other terminal connected with electro-magnet 3 25 by means of a conductor 22. Contact 19 is adapted to engage with 14 only when the latter is in its down or off position and is sometimes used for setting combinations but as it does not relate to the present invention, it need not be 30 further here discussed. Contact 24 is adapted to engage with 14 only when the latter is in the up or on position and is connected by conductor 25 with the other terminal of the electro-magnet 3, therefore, when key 5 is in its down or on 35 position and, therefore, yoke or arm 14 in its corresponding up position, magnet 3 is energized, and through the operation of auxiliary apparatus, air is admitted to chest 1 so that pipes 4 planted thereon will speak when the proper manual keys are touched by the player.

In the operation, let it be assumed that the key 5 is in its "off" position shown in Figure 1. The yoke or arm 14 is then in engagement with the contact 18 but not with 24. It is, of course, also 40 in engagement with contact 19 but as that feature has nothing to do with the present invention it may be disregarded. If the stop key 5 be moved downwardly into its "on" position while the lock bar 17 is in its forward position, that is, 45 in obstructing relation to the projecting end of the yoke or arm 14 so as to prevent movement thereof, the only immediate result is the upward swinging of the segment 9 and compression of the spring 13, the yoke or arm 14 still remaining 50 out of engagement with the contact 24. If the stop key 5 be moved downwardly into the "on" position while the lock bar 17 is in retracted position, or in non-obstructing relation to the end of the yoke or arm 14, or if the lock bar be 55 retracted subsequent to the downward movement of the stop key 5, the yoke or arm 14 will be forced upwardly by the spring 13 and will engage the contact 24, thus completing the circuit from the source 21, conductor 20, contact 18, yoke or arm 60 14, contact 24, conductor 25, electro-magnet 3, and conductor 22 back to the source 21. This energizes the magnet 3 and places the rank of pipes 4 in condition to be operated by the man- 65 uals in the usual manner.

If the player wishes to use this particular stop while preparing for a change in registration which does not require it, he then through appropriate mechanism, not shown, brings the lock bar 17 to its forward position, whereupon it will engage beneath the yoke or arm 14 which has been thrown to its elevated position, as above described. At a convenient time he would then lift the key 5 to its "off" position, either directly by hand, or through the operation of a visible 70 75

combination wherein this stop is set to be "off", but this would have no immediate effect on the yoke or arm 14 which would be held elevated by the lock bar 17, the circuit being closed through the contacts 18 and 24. When it is desired that the proper change in registration shall become effective, the player releases the lock bar 17 whereupon all the yokes or arms 14 which are forcibly held away from their normal relative positions with respect to their segments 9 will immediately resume their normal positions through the withdrawal of the lock bar. By this means, it is clear that while playing any particular registration, that is to say, with any desired number of different stops in their "on" or "off" positions, the player may move the stop keys without affecting the registration played at that particular time. This may be done at leisure, that is to say, at any convenient times during the playing in a certain registration so that the player is not under the burden of hurriedly throwing the stops on or off by hand, or by pressing several visible combination pistons as described above at the conclusion of a certain musical passage preparatory to playing another passage requiring a different registration. Furthermore, the position of the stop keys will indicate what the next registration will be. As many of the stops may be thrown into "off" or "on" position as may be desired in accordance with the requirements of the musical composition being played and corrections or changes in the future registration may be made without making any immediate change, the present registration being maintained by the cooperation of the lock bar with the yokes or arms 14 regardless of whether they be in the "off" or the "on" position, the change in registration occurring only upon release of the lock bar.

The same general action can be brought about by the use of the electrical means shown in Figure 4 instead of the above described mechanical means. In this modification, the segment, locking bar, and associated parts are omitted and are replaced by a simple contact blade 26 carried by the stop key 27 corresponding to the key 5, this blade being always engaged by a contact 28 and adapted to be brought into engagement with selected contacts 29 and 30 which are connected, respectively, by conductors 31 and 32 with electro-magnets 33 and 34 positioned at opposite sides of and adapted to attract an armature 35 carried by a pivoted contact arm 36 adapted to engage and bridge a pair of contacts 37 and 38, the former of which is connected by a conductor 39 with one terminal of the electro-magnet 3 and the latter of which is connected by a conductor 40 with the contact 28. The source of current 21 is connected with the conductor 40 and by a conductor 41 with the other terminal of the electro-magnet 3. The other terminals of the electro-magnets 33 and 34 are, of course, connected to the return side of the source 21, but as it is desirable to lock the stop action contacts temporarily while preparing a future registration it is necessary to have a circuit interrupter interposed in this connection. While any convenient switch device may be provided for the purpose I have, for the sake of illustration, shown a key 42 similar to the stop key 27 and carrying a contact 43 always engaging a contact 44 connected with the source by a conductor 45. The contact blade 43 is movable into or out of engagement with a stationary contact 46 to which the second mentioned terminals of the

electro-magnets 33 and 34 are connected by conductors 47 and 48.

In the operation of this form it will be observed that the contacts 37 and 38 correspond to the contacts 18 and 24. When the key 27 is thrown downwardly into its "on" position the blade 26 engages the contact 29 so that the circuit is closed from the source 21, conductor 40, contact 28, blade 26, contact 29, conductor 31, electro-magnet 33, conductor 47, conductor 43, contact 46, blade 43, contact 44, and conductor 45, back to the source. The electro-magnet 33 is thus energized and attracts the armature 35, resulting in movement of the pivoted contact 36 into bridging engagement with the contacts 37 and 38. When this occurs current flows from the source 21, through the conductor 40, contact 38, contact arm 36, contact 37, conductor 39, electro-magnet 3, and conductor 41, back to the source, thus energizing the electro-magnet 3 and placing the rank of pipes 4 in condition to sound upon depression of the manual keys. In order for this action to occur, it is necessary that the key 42 be in circuit-closing position, as it is clear that if the key 42 be in circuit breaking position movement of the stop key 27 to engage the contact plate 26 with either the contact 29 or the contact 30 will have no effect. Clearly then, if the switch key 42 be in the "off" or circuit breaking position the stop key 27 may be moved into either "off" or "on" position while playing in a certain registration without causing any change in the registration until the switch key 42 is closed. As long as the switch key 42 is closed changes in the present registration are effected by moving the stop key 27. Assuming that the stop key 27 is in the "on" position and the player desires to omit that stop in the next registration, it is merely necessary, while the switch key is open, to throw the stop key 27 to the "off" position to bring the blade 26 into engagement with the contact 30 so that when it is desired to throw the future or advance set registration into action mere closing of the switch key 42 will cause current to flow from the source 21, through the conductor 40, contact 28, contact blade 26, contact 30, conductor 32, magnet 34, conductor 48, contact 45, contact blade 43, contact 44 and conductor 45, back to the source, the resultant energization of the magnet 34 attracting the armature 35 and withdrawing the contact arm 36 from bridging engagement with the contacts 37 and 38. This breaks the circuit through the electro-magnet 3 and renders the particular rank of pipes 4 inoperative. It is apparent that at all times individual manual control of the stop action as well as advance setting thereof may be very conveniently accomplished.

In Figure 5, I have illustrated an electro-pneumatic system or arrangement embodying a relay following the general principle disclosed in the form just described. In this modification I have shown an air chest 50 with a chamber 51 therein containing an air pressure normally above that of the atmosphere. For each stop action to be controlled there is the following mechanism: A puff or diaphragm 52 covering a chamber 53, a puff or diaphragm 54 covering a chamber 55, a rod or its equivalent 56 connecting both diaphragms, contacts 57 and 58, and an electro-magnet 59. These are the general elements which are combined with and related to the various detailed features to be described. The contacts 57 and 58 are located at opposite sides of the rod 56 and are mounted on a suitable insulating support 60, their free ends being directed inwardly.

or toward each other, as at 61, so as to be capable of bridging engagement by a contact 62 carried by the rod 56 and preferably adjustable therealong as by the means disclosed. A suitable packing 64 is provided where the rod 56 passes into the chamber 55 from the chamber 51. The chambers 53 and 55 communicate through passages 65 and 66 and the latter leads to a small chest 67 having a release port 68 normally closed by an armature 69 adapted to be attracted by the poles of the magnet 59. The small chest 67 communicates with the chamber 51 through a pressure port 70.

The control means for this pneumatic mechanism may include a stop key 71 somewhat similar or corresponding to the stop keys 5 and 27 and mounted in the same or any other preferred manner. This stop key carries a contact 72 always in engagement with a contact 73 and adapted to engage a contact 74. The source of current 21 has one terminal connected by a conductor 75 with the contact 73 and has its other terminal connected by a conductor 76 with one terminal of the electro-magnet 59, the other terminal of which is connected by a conductor 77 with the conductor 74. The first-mentioned terminal of the source is connected by a conductor 78 with one terminal of the electro-magnet 3, the other terminal of which is connected by a conductor 79 with the contact 58. The contact 57 has connected therewith a conductor 80 leading to the second-mentioned terminal of the source 21.

In the operation of this form of the invention, assuming that the parts are initially in the position shown in Figure 5, it will be seen that when the player depresses the stop key 71 to the "on" position the blade 72 will engage the contact 74 and, of course, the contact 73. When this is done current will flow from the source 21, conductor 75, contact 73, contact plate 72, contact 74, conductor 77, electro-magnet 59, conductor 76, back to the source 21. The resultant energization of the electro-magnet 59 causes attraction of the armature 69 which closes the pressure port 70 and uncovers the release port 68. Air pressure within the chambers 53 and 55 then exhausts through the passages 66 and 65 into the chest 67 and thence out through the port 68. As the pressure within the chamber 51 is greater than atmospheric, the diaphragm 52 is forced to the left, resulting in corresponding movement of the rod 56 so that the contact 62 thereon will engage against the end portions 61 of the contacts 57 and bridge them, thus closing the circuit from the source 21 through the conductor 78, electro-magnet 3, conductor 79, contact 58, contact 62, contact 57, and conductor 80, back to the source. The resultant energization of the electro-magnet 3 places the pipes 4 in that particular rank in condition for sounding upon depression of the manual keys. When the stop key 71 is thrown to the "off" position so that the blade 72 disengages the contact 74, the circuit just described is broken at this point and the magnet 59 is deenergized, permitting the armature 69 to drop and close the release port 68 and open the pressure port 70. Pressure within the chamber 51 then passes through the port 70, chest 67, and passages 65 and 66 into the chambers 53 and 55, bulging the diaphragm 54 to the right and causing corresponding movement of the rod 56 so that the contact 62 will disengage the ends 61 of the contacts 57 and 58, thereby breaking the circuit through the electro-magnet 3 and rendering the 75 associated rank of pipes 4 inoperative. The pres-

sure in 53 and 51 being equal, diaphragm 52 moves to the right without resistance when rod 56 is moved by diaphragm 54.

In order to prepare for registration and lock the stop action in the last position, it is merely necessary that the player relieve or release the air pressure from the chamber 51, and while thus released the energization or deenergization of the magnet 59, by movement of the stop key 71 into one position or the other, will have no effect on the rod 56 which will remain stationary for the reason that atmospheric pressure only is on both sides of both diaphragms 52 and 54. When air pressure is restored within the chamber 51 the rod 56 will at once respond to control by energization or deenergization of the magnet 59. To prevent the rod 56 from drifting one way or the other when the pressure is relieved in the chamber 51, I may provide a drag device which may be simply a pair of springs 81 mounted on the support 69 and frictionally engaging the end portion of the rod. Means for releasing or restoring the air pressure within the chamber 51 may conveniently be similar to any of the several forms of chest action, one of which is shown in Figure 6 which shows a longitudinal section of one end of chest 50, and to which is attached action chest 82 the interior of which is supplied with pressure air from pipe 83. Top board 84 of chest 50 is provided with exhaust opening 85 adapted to be closed by valve 86, and bottom board is provided with opening 87 into 82, adapted to be closed by valve 88, both 86 and 88 being connected as by rod 89, which is connected through arm 90 with movable member of bellows 92. Passage 93 connects interior of 92 with small chest 94, which has pressure port 95 connecting with 82, and exhaust port 96. Armature 97 is adapted to close either 95 or 96 upon the energizing or deenergizing, respectively, of magnet 98. During normal control of the stop and coupler actions by the manual means, 98 is energized, closing the port 95, and opening the port 96 so that pressure in 82 holds bellows 92 in the collapsed position, drawing down rod 89, closing exhaust opening 85, and placing 51 in communication with 82 through 87 whereby pressure in 51 and 82 is equal and the several rods 56 will respond to the action of their respective keys 71.

When 98 is deenergized through breaking of contact by device similar to 42, 43, 44, and 46, Figure 4, armature 97 falls closing 96, opening 95, allowing pressure air from 82 to pass through 95, 94 and 93 into bellows 92, expanding it and thereby raising 89, closing opening 87 by valve 88, thus cutting off flow of pressure air from 82 into 51, and by simultaneously lifting valve 86 from opening 85 allowing pressure in 51 to be reduced to atmospheric through escape of pressure through 85.

From the foregoing description and a study of the drawings it will be apparent that I have thus provided several ways of accomplishing the general object of the invention, there being no particular restriction as to the precise details disclosed as they may be readily varied. Summing up, it will be clear that with an organ equipped with the stop action system disclosed in this invention, the player may at his option control the registration in the usual manner by hand movement or stop and coupler controls, or by the visible combinations, at the moment of desired change, or by closing a special switch, the organ will remain under control of the registration as last set, until the said special switch 75

is released. During the period of special switch control the player may visibly change the combinations by pistons or toe stud or by hand, or by both methods, and these changes can be 5 made or altered at convenient intervals and will not control the actual registration until the special switch is released. The player, therefore, can see the actual future registration and correct it if necessary before he actually uses 10 it. The number of visible combinations may, therefore, be reduced if desired as one which is approximately correct can be used and afterwards altered by hand. It is believed that the 15 construction, operation and advantages will be readily apparent to one skilled in the art without further explanation.

While I have shown and described the several preferred embodiments of the invention, it should be understood that the disclosure is 20 merely illustrative of an exemplification of the principles involved and that the right is reserved to make many changes in the arrangement and combination of parts, and particularly in the detailed construction, provided such variations and 25 modifications constitute no departure from the salient features of the invention or the scope of the claims hereunto appended.

This application is a substitute for applicant's prior application, Serial No. 306,726, filed September 18, 1928, which has since become abandoned.

Having thus described my invention, what I claim is:—

1. In an organ, in combination with stop actions, stop keys normally indicating by their position whether such stop actions are on or off, each key carrying means for closing an electric circuit, pneumatic control means operated by said circuit for effecting desired movement 40 of said stop actions, and means for rendering said pneumatic means ineffective, whereby the action of said circuit closing means may be delayed until said pneumatic means is rendered effective.

45 2. In an organ, a stop action and registration control, said registration control comprising a stop key and secondary control means associated therewith, said stop key having means associated therewith for actuating its stop action, said secondary control means selectively rendering said actuating means effective and ineffective to cause operation of said stop action upon actuation of said stop key.

50 3. In an organ, stop actions and registration controls, each control comprising a stop key and secondary control means associated therewith, each stop key having means for actuating its stop action, said secondary control means serving, when in one position, to operatively disconnect said stop actions from the control of said keys, and movable to another position to restore control to the stop keys, so that the stop actions will respond to the stop key settings.

55 4. In an organ, stop actions and registration controls, each control comprising a stop key and secondary control means associated therewith, each stop key having means for actuating its stop action, said secondary control means serving, when in one position, to operatively disconnect said stop actions from their controls, and movable to another position to restore control to the stop keys, so that the stop actions

will respond to the stop key settings at the time of such movement, and means for moving said secondary control means to either position.

5 5. In an organ, stop actions and registration controls, each control comprising a stop key, said stop keys being adapted for individual manual movement and also for group movement, and normally indicating by their positions whether said stop actions are on or off, secondary control means associated with said stop keys, and means for moving said secondary control means to one position to operatively disconnect said stop actions from the control of the respective keys, or to another position to restore control to the stop keys, so that the stop actions will then 15 respond to the settings of said keys at the time of such movement.

6. In an organ, stop actions and registration controls, each control comprising means for normally operating said actions and adapted for 20 individual manual movement and also for group movement, and secondary control means associated with said operating means, actuating to operatively disconnect said stop actions from their control when in one position and movable 25 to another position to restore control to said operable means, so that the stop actions will respond to the settings of said means.

7. In an organ, registration controls comprising stop keys, stop actions normally controlled 30 by said keys, and secondary control means which in one position operatively disconnect said stop keys from the respective stop actions, thereby permitting said keys to be moved to a desired setting without affecting said stop actions, and 35 in another position restores the connection between said stop keys and stop actions so that the latter automatically respond to the settings of the stop keys at the time of restoration.

8. In an organ, in combination with stop actions, stop keys normally indicating by their position whether such stop actions are on or off, a segment carried by each key, a yoke straddling each segment, means pivotally mounting said 40 keys and yokes for relative movement, resilient 45 means mounted on each segment and tending to maintain the associated yoke in a given position with respect thereto, locking means for holding each yoke in a given position irrespective of the position of the associated key, and means 50 for connecting said yokes to said stop actions.

9. In an organ, in combination with stop actions, stop keys normally indicating by their position whether such stop actions are on or off, means for closing an electric circuit carried by 55 each key for effecting desired movement of the stop actions, and secondary control means for said electric circuits, whereby the action of said circuit closing means may be delayed until corresponding actuation of said secondary means.

10. In an organ, stop actions and registration controls, each registration control comprising a stop key, and secondary control means associated with said keys, each stop key having means associated therewith for normally actuating its stop action in accordance with the setting of the key, and said secondary control means being movable to one position to prevent, and to another position to permit, actuation of said stop actions, through said actuating means, to conform with the key settings.
